United States Patent Office

Des. 183,407

Patented Aug. 19, 1958

183,407

COMBINED SEAT AND EASEL

George E. Schaefer, Muskegon, Mich., assignor to Hamilton Manufacturing Company, Two Rivers, Wis., a corporation of Wisconsin

Application February 27, 1957, Serial No. 45,018

Term of patent 14 years

(Cl. D15—8)

Fig. 1

Fig. 2

Figure 1 is a perspective view of a combined seat and easel, showing my new design; and

Figure 2 is a bottom plan view thereof.

I claim:

The ornamental design for a combined seat and easel, substantially as shown.
